UNITED STATES PATENT OFFICE

SHERMAN A. THOMAS, OF ROCHESTER, NEW YORK

DESIGN FOR A COMBINED HAT SUPPORT AND COAT HANGER

Application filed November 4, 1929. Serial No. 33,318. Term of patent 14 years.

To all whom it may concern:

Be it known that I, SHERMAN A. THOMAS, a citizen of the United States, residing at Rochester, in the county of Monroe and State of New York, have invented a new, original, and ornamental Design for a Combined Hat Support and Coat Hanger, of which the following is a specification, reference being had to the accompanying drawing, forming part thereof.

In the drawings:

I claim:

The ornamental design for a combined hat support and coat hanger as shown.

In testimony whereof I affix my signature.

SHERMAN A. THOMAS.
